[57] CLAIM

The ornamental design for a surgical leg clamp, as shown and described.

DESCRIPTION

FIG. 1 is a perspective view of a surgical leg clamp showing my new design;

FIG. 2 is a side elevational view thereof, the opposite side being a mirror image;

FIG. 3 is a top plan view thereof, with the strap shown fragmentarily for convenience of illustration;

FIG. 4 is a left end elevational view thereof;

FIG. 5 is a right end elevational view thereof.

FIG. 1

FIG. 2

—FIG. 3

—FIG. 4

—FIG. 5
